UNITED STATES PATENT OFFICE

CLARENCE R. MARTINEAU, OF ALBANY, NEW YORK

CAR DOOR LOCK

Application filed April 11, 1929. Serial No. 354,267.

This invention relates to improvements in seals and sealing mechanism for the doors of railway cars and the like, such as set forth in patent granted to me No. 1,578,289 of March 30, 1926. In said patent, after the car door is locked by bolt, a destructible lock in the form of a seal or check is inserted in a notch in the bolt and interlocks therewith, so that the bolt cannot be withdrawn without destroying this lock or seal, and thus evincing that there has been tampering with the lock; the seal being normally visible at all times through a glass front. Neither can the seal be withdrawn except by destroying it; and the substitution of a new seal would be promptly detected because of the fact that the new seal would not have the correct individual number.

One of the features of the present invention is to avoid injury to the fragile locking-seal by reason of the jumping and falling of the heavy hasp-bolt during the travel of the railway car; and for this purpose the bolt is not locked directly by the fragile seal, but is locked by means of a tumbler, which is of strong construction, and is so mounted that it does not tend to jump up and down. The fragile seal interlocks with said tumbler, and is not apt to be injured thereby, while the tumbler interlocks with the hasp-bolt.

According to the present invention, upon the car door being closed, a hasp on the door is swung over a lug on the car fixture, and a pin or bolt is dropped through the lock in front of the hasp to retain the latter. A tumbler is then manually rocked into locking engagement with the pin or bolt, to prevent the latter from releasing the hasp. Then a locking-seal is thrust up endwise through a slot in the floor of a housing in which the tumbler and the bolt are confined, this seal interlocking with the tumbler to prevent movement of the latter. The seal is thrust up far enough to reach the bite of a pair of mutilating gears, which are operated by a handle to draw the seal entirely within the housing. The tumbler is so mounted and the locking-seal is so placed that the tumbler has little or no effect in injuring the seal while the car is under way.

Other features and advantages will herein-after appear.

In the accompanying drawings,

Figure 1 is a sectional elevation through the housing, the check and the mutilating gears, showing a seal being thrust up and caught by the gears. 55

Figure 2 is a perspective view of the present improvements secured to the side wall of a railway car, and holding the car door locked, and illustrating the manner of inserting a seal, point upwardly, into the seal-box or car lock. 60

Figure 3 is a perspective view of one end of a mutilated seal ejected from the lock. 65

Figure 4 is a perspective view of the bottom of the lock, showing the manner of presenting a seal up through the bottom, and also showing the end or handle of the tumbler which locks the hasp-pin. 70

Figure 5 is a perspective view of the preferred form of seal.

Figure 6 is a perspective part-sectional view showing in section the lower part of the lock or seal-box, with parts broken away to disclose the tumbler, the U-shaped sealing pin and other parts. 75

Figure 7 is a perspective plan showing the seal-chute or way in section, and illustrating how the seal-chute is filled by the seal so as to close it against the introduction of another seal. 80

Figure 8 is a rear elevation of the device detached from the car, and showing much of the open interior of the housing, and its contents, and also showing the hasp-pin dropped to normal locking position, and the tumbler normally withdrawn therefrom. 85

Figure 9 is a perspective view of the preferred form of check or seal, showing a main stiffening rib formed therein and of considerable length, while shorter ribs, one on each side of the main rib, co-operate therewith to fill up the seal-way in the lock. 90

Figure 10 is a perspective view showing separated details of the lock or housing, including the windowpane and its framing, and also including the seal-chute, the mutilating gears, etc. 95

Figure 11 is a perspective view of the train 100

of mutilating gears and operating wheel and housing.

Figure 12 is a side elevation showing the tumbler in normal released position, and also showing the tumbler-slot in the hasp-pin. This view shows the mutilating gears, and also the seal-slot which is provided in the tumbler and enables the seal to pass into the bight of the gears when the tumbler is in locking position.

Figure 13 shows a blank from which one form of seal may be finished.

Figure 14 shows another modified form of seal.

Figure 15 illustrates one means for preventing introduction of an improperly formed seal.

Figure 16 shows grooves or slots in a glass pane, permitting the introduction of an authorized seal, but preventing introduction of spurious seals.

Figures 17 and 18 are face and side views of a seal interceptor in the form of an obstruction placed in the housing to intercept spurious seals.

Figure 19 shows another form of intercepting device.

The lock, which is designated generally as 10, is placed upon the side 11 of a railway car 10 or other receptacle. Upon the door 12 of the car is hinged the usual hasp 13, having a slot 14, which catches over a lug 15 projecting from a front wall 16 of the lock. A pin 17 may be dropped through a hole 18 in the lug, thereby locking the hasp. Said pin is guided up and down in a perforation 22 formed in the flooring of the lock-housing. It also has an upper guide in a hole 19 which is formed in the bottom of a compartment 20 projecting forwardly from the lock, Figure 6, the floor of said compartment 20 performing the function of a rigid lug to cooperate with said lug 15 for retaining the hasp, the tongue of which is confined between said lug 15, and compartment 20.

One of the objects of the invention is to provide a door-lock which is both strong and compact; and in order to meet the requirement for compactness the difficulty due to the great length of the usual pin is overcome by bending the pin into the form of an inverted U, of which the longer leg or portion 21 is used mainly for guiding purposes, as it works in perforation 22 formed in the flooring 23 of the lock. This leg 21 projects down beyond the bottom of the lock, to form a hand-hold, whereby the entire U-shaped hasp-pin may be raised, whenever it is desired to either open or close the car; and it may be dropped in order to secure the hasp. The cross-piece 24 of the U rests upon the bottom of the compartment 20.

One side edge of the lock-housing is in the form of a vertical plate 25, standing at right angles to the side of the car 11, and forming

an abutment against which the car door 12 is closed. The long leg 21 of the U pin may extend a little below the abutment 25, for convenience of the operator in finding the pin in the dark; and the flooring at 23 may be at a sufficient elevation to permit the necessary upward range of movement of the pin while the leg 21 still remains caught in the guiding hole 22. The guiding holes 22, 19 cooperate to guide the entire pin unit, while the locking pin 17, being restricted by the hole 19, prevents rotation of the unit about the leg 21 as an axis. As viewed from the inner side, it will be seen that the interior of the compartment 20 forms a groove 26 in the front wall 16, see Figure 8. The pin is kept within the groove by means of a fixed guiding arm 27 forming part of the framework.

Another advantage gained by bending the hasp locking pin into U form, is that a groove or locking shoulder 28 may be formed in the leg 21, into or over which may catch a hook 29 forming a tumbler which is pivoted at 30 upon the framework, and counterweighted at 31 to keep the hook released.

After the hasp has been closed and the pin 17 has been dropped into locking position, a handle 32 upon said tumbler 29 may be lifted, thereby swinging the tumbler or hook 29 over the shoulder 28 upon the locking pin 21. Other forms of tumbler than the hook form may be employed, and other means for holding the tumbler released; and a finger-piece may be provided otherwise than upon the weighted arm 31.

The tumbler itself is retained in locking position by means of a destructible seal, designated generally as 33, which fits in a slot 34 formed in the tumbler 31. It can be passed into the slot when the tumbler is in locking position, but not when it is in the open position, seen at Figure 12. This seal is held in a chute 42, 43 against edgewise displacement, and hence retains the tumbler in locking position. This seal is visible through a vertical front window 35, which closes an opening 36 in the front wall of the lock, and enables the individual numbers 37 of the seal to be read, as well as other data 38 thereon, and permits generally an inspection of the main portion of the seal to discover if it has been tampered with.

The seal may have a reduced or bluntly pointed leading end 39, Figure 5, for ease of introduction in a seal-slot or perforation 40 formed in the bottom 41 of the lock.

Rising from the slot 40 is a seal-chute within the lock, including a rear wall 42 and side-guiding walls 43. Just sufficient space is left in the chute between the back 42 and the glass windowpane or light 35, to permit the passage of the seal with its raised figures and letters 37, 38. The walls 43 interlock with the seal, to enable the seal to lock the tumbler 29 against movement.

The chute and the seal therein are confined between the glass light 35 and the tumbler 29, 31, Figure 1, so that the seal rises in front of the tumbler. As the point of the seal nearly rises to the height of the slot 34 in the tumbler, it encounters a fixed deflector 44 within the lock, which may be set at an angle of say 30 degrees to the rising seal. The seal-chute at its upper portion may be inclined a little rearwardly. Figure 1, so as to present the point of the seal at a more favorable angle to the fixed deflector 44. It will be noticed that one or more recesses 45 may be cut in the rear face of the glass pane 35, to accommodate the forks 44 which form the deflector. The deflector is forked so as to clear the raised portions 37, 38 along the middle of the seal. At the top, the deflector may be fastened by a screw 46 to the rear of a bracket 47, which includes a rear wall 48, forming a backing for the chute and also includes a frame 49 for the window.

When the leading end of the seal encounters the deflector 44, it is fixed or bent toward the left at Figure 1, and takes a curved path and enters the bight of corrugating rolls 50, 51, having intermeshing teeth 52, by which the seal is corrugated throughout its length as at 53. The rolls are rotated by a key or handle 54 that is fixed upon the end of a shaft 55, which is connected by a one-way clutch 56 to a gear-shaft 57 having gear 51 thereon. Any attempt to return this seal by means of the handle 54 would be fruitless, because the one-way clutch 56 renders the hand-wheel 54 incapable of rotating the gears. Moreover, a spring-dog 58 engages the teeth of gear 51 to prevent it from being rotated backwardly.

In using the device, the car door 12 is closed against the abutment-plate 25 of the lock, and by means of the pendent long leg 21 the hasp-pin 17 is lifted clear of the lug 15, whereupon the hasp 13 is closed over said lug 15, and then the hasp-pin is dropped, thereby retaining the hasp. At this time the tumbler 29, 31 is in normal withdrawn position. By means of the finger-piece 32 said tumbler is now swung over into locking position, see Figure 6, with the hook 29 catching over the shoulder or in the slot 28 formed in the long leg 21 of the hasp-pin. At this time the slot 34 in the tumbler is in line with the seal-chute 42, 43. The operator then thrusts up a seal through the opening 40 into the chute until the leading end of the seal strikes the deflector 44 and is bent and deflected thereby through said opening 34 into the bite of the corrugated rolls 50, 51, whereupon the handle 54 is turned to draw the seal entirely within the lock. The seal therefore interlocks with the tumbler, so that the car door cannot be opened; and it is the intention that a new seal cannot be used until the first one has been destroyed and ejected by means of said rolls;

the railroad operative not being provided with duplicate numbered seals, and the insertion of a fresh seal having the wrong number thereon leading to detection.

To go more into detail, it will be seen that in the normal position of the members, the hasp 13 hangs loosely upon the car door, and the hasp-pin 17 is in its bottom position. The tumbler 29, by reason of its shape and its pivoting is so weighted as to bring its normal position to the left, with the handle 32 protruding down through the bottom, this protruding portion being found in the hand opening 75 at the left of the lock.

The car door is now closed, and with the left hand the long leg 21 of the U-shaped hasp-pin is raised as far as it will go. While it is held in that position, the hasp 13 is placed over the hasp-lug 15, by using the right hand. The left hand now permits the hasp-pin to drop, the short leg of the hasp-pin dropping through the hasp-lug in front of the hasp, thereby preventing the hasp from opening. While this does not actually lock the door, it does prevent the door from working open. The left hand is now placed in the hand opening 75 at the left under side of the lock, and presses the tumbler-handle 32 up as far as it will go, thus rocking the tumbler 29 so that it enters the locking groove 28 on the hasp-pin. While the tumbler is held in this locking position by the left hand, the right hand introduces a check-seal 33 into the slot-way 40, pushing it right up and through the deflector 108, 44, and through the tumbler slot 34. This seals the locking bolt in its locked position. The left hand can now be released and placed on the turn handle 54, and turns the handle to the left, or away from the operator. At the same time the right hand presses the check-seal 33 farther up into the slot-way 40, and the rotated gears will now take hold and draw the check-seal entirely within the lock, at which time the operator stops turning the key or handle 54. As the hasp-pin 17 prevents the hasp 13 from being opened, and the tumbler 29 is in locked engagement with the groove 28 in the hasp-pin 21, and the check-seal 33 locks the seal-locking bolt 29 against falling back to its normal position, and the gears 50, 51 are locking the check-seal, and the ratchets 56 and detent 58 lock the gears against reverse movement, it will be seen that the car is actually locked and sealed, and cannot be opened except by the advance and removal of the check-seal 33. The seal is sufficiently strong to retain the tumbler in its locking position, Figure 6, and the tumbler is so positioned that the jarring, due to the traveling of the railway car, does not appreciably injure the seal. Assuming that the record, as per indicia on the seal, has been duly registered by the seal takers, etc., the car is placed at the platform ready to be opened. This is accomplished by merely

120
125
130

turning the handle 54 to the left, thus sending the check-seal through the gears, and ejecting the same through chute 101 into the inside of the car, in a cut up mutilated condition. This operation of ejecting the check-seal releases the tumbler 29, which settles back into its normal position, and by so doing withdraws from locking the groove or shoulder 28 in the hasp-pin 21, thus permitting the latter to be raised, and the hasp to be removed from the hasp-lug, and the door opened. When the tumbler is in a normal position, the seal-slot 34 is entirely out of register with the seal slot-way 42, and for that reason no seal of any description can find its way between the gears; and it is for this reason that the push end 32 of the tumbler is hidden, thus preventing a large percentage of unauthorized persons from perceiving the manner of operation.

20 A canopy 59 may form an extension of the top of the housing 10 at one side of the latter, and overhang the window 35 and the hasp 13, hasp-pin 17 and other parts, to protect them from the weather.

25 The U-shaped hasp-pin 17, 21, 24 is mainly confined within the housing to protect it from burglars as well as the weather.

20 The housing may be placed along the side wall of the car and secured by bolts 60, 61, 62, the bolt 60 passing through a flange 64 extending above the housing, and the bolts 61, 62 passing through the wall of the vertical compartment 20 which contains the hasp-pin, and bolt 63 passing through an ear 65 at one side of the housing. The housing is open or unprovided with a wall at its rear side, but the edges of its side walls are bolted against the side of the car, thus completing the enclosure for the mechanism.

30 At its lower portion there may be formed upon the housing a projecting lug 66, having therein a hole 67, for convenience in attaching a padlock or other means for greater security in locking the car door. This hole may also be used as a device in which to hang bale hooks or tally strips temporarily.

35 There may be provided upon the casing a projecting guide 68, to overlap the car door and to guide the door when closing. This part 68 may also serve as a support for the door, as it will relieve the hasp of strain in the event of the load within the car shifting against the car door.

40 The upper and lower extension-plates 25 of the side wall of the housing are stiffened by the upper and lower flanges 64, 69 at the rear of the boxing, and solidly withstand the edge-wise thrust of the car door after the same is locked and when the train is in motion.

45 The seal-receiving slot 40 is in the very bottom of the housing, where it is safe from the weather, the seal being thrust endwise upwardly into said slot, Figures 1 and 4.

50 At the leading end of each seal, one corner is cut off diagonally at 70, giving a special

shape to the end of the seal, rendering it irreversible. This asymmetrical end fits in a groove or depression 71 formed on the under side of the box floor 41, Figure 4. When the seal is properly presented to this groove, it is found to fit, and the groove may guide the user in slipping the seal along the floor until it reaches the slot 40 and is pushed up therein. The seal is intended to go into the lock only one way. If the seal were turned around, its tip would not fit in the groove 71, and the user would thereby be informed that the seal was not properly positioned, even in the darkness. The same difficulty would happen if it was attempted to insert the seal wrong end up. The grooving or shaping of the bottom of the box 41 is therefore such that it will easily receive and lead or guide the seal to the slot, when the advance end of the seal has been properly presented.

55 The groove-portion of the slot is bordered by a ledge 72, which is provided to assist the fingers of the operator in feeling for the slot; and this ledge may be continued at 73 at the side 16 of the boxing. The side ledge 73 may be arched to form protection against the weather.

60 A hand opening 75 is provided in the bottom of the box at its left-hand portion, as a convenience in reaching and locating the lower end 32 of the hook 29, for the purpose of entering the hook in the slot 28, prior to inserting the seal 33 for maintaining the hook in its seal-locking position.

65 The hasp-pin is U-shaped, the shorter leg to pass through the hasp-lug 15, and at the end of the short leg of the hasp-pin is provided a slot 76, which slot registers with the slot 67 in the hasp-pin registering lug, for convenience in attaching a padlock if desired. The longer leg 21 is mostly hidden inside of the lock, and the lower portion of it is raised and lowered through the hole 22 provided for that purpose in the bottom of the box. A hole 77 is provided in the extreme bottom end of the hasp-pin, for the purpose of entering a bale hook or a like instrument to pull the hasp-pin down, should it stick.

70 On the confined or hidden portion of the hasp-pin the locking groove 28 is so positioned as to make burglar access impossible.

75 The seal-receiving, seal-destroying and seal-ejecting unit 80 is provided on the left side of the lock. This unit is inserted into the box from the rear, before the box or lock carrying it is attached to the car; said box being entirely open on its rear side, which is placed against the car wall. Said seal-receiving, destroying and ejecting unit includes a box-like frame 81 which is provided with an upper right-hand corner hole and a bottom left-hand corner hole through the body of the unit, through which long machine screws 78 and 79 are inserted for securing the unit detachably to the inside of the front wall 16

of the lock casting. An integral portion of this unit is a thick boss or bearing 82, through which a large hole is bored.

At the outside or front edge of the boss a rib or bead 83 is cast to deflect rain, thawing, etc. In a slanting front wall or portion 84 of the box a hole or slot 85 is provided, the slot being open in the rear, to permit assembly of the unit within the main boxing. The unit includes a slanting wall-portion 86 which is so shaped as to close up the opening 85 in the bottom of the lock, so that burglar manipulation of the interior of the lock from this side is made impossible.

An extension 87 is provided on the right of the unit 80, into which pivot 30 is placed; and also on the right is an upper projecting integral arm 27 for the purpose of keeping the U-shaped hasp-pin 21 in position. In the arm is threaded a set-screw 89, which serves as an adjustment for the proper general positioning of this unit in the lock. The screw is provided with a nut 90.

On the back of the unit, and cast integral with the frame thereof, is a boss 91 provided with a slot 92 through which the mutilated seal is ejected.

The walls of the unit 80 serve as a rest or seat for the seal-guide. In the upper portion of the unit 80 there is provided an opening 93 into which are arranged the upper and lower meshed gears 50, 51, the upper gear 50 being an idler mounted upon a shaft 94, upon which also are mounted, on either side of the gear, hardened collars 95, 96, Figure 12. The lower gear 51 is keyed on shaft 57, the forward end of which shaft is enlarged and forms a ratchet-clutch, or back-check 56, Figure 2. Meshing with this ratchet and taking its bearing in the thick boss, is another clutch or ratchet 97, extending its shaft-portion 55 outside of the boss 82, and to its extending end is secured the turn handle 54. When the outer ratchet-member 97 is idly turned in clockwise direction, the ratchet 56 remains stationary, and shaft 55 is forced outwardly. A screw or stop 99 which is placed in the path of the outer ratchet, prevents the same from being withdrawn too far. The clutch-members are so made as to permit of the turning of the mutilating gears in one way only; and a turn on the handle in the reverse direction merely turns the handle-ratchet idly. As a further lock against a reverse movement of the gears, the flat detent 58, which is positioned against the lower gear 51, is held in position by a screw 100 in the lower portion of unit 80.

Between the two gear-shafts, and so positioned as to receive the destroyed seal as the same is ejected from the gears, is the chute 101, which projects into seal-ejecting boss 91 at the back of the seal-unit 80.

Through slot 34 in the seal-locking bolt

or tumbler, the seal enters the gears. At the lower left end of the bolt or hook 29 is the extended portion 32 forming a handle, which passes through a hole 102 in the wall of the unit at the left, Figures 2, 12. The bottom right portion of this bolt is provided with a pivot-hole through which the pivot 30 extends. The seal slot-way 47 is placed on its seat, and is enclosed by the walls provided to receive the same. After the windowpane 35 is placed in position, the entire unit 80 is securely screwed to the front wall of the lock by screws 78, 79. Unit 80 is provided with front flanges 103, 104, 105, for the purpose of seating against the front walls of the lock or boxing. Rear flange 106 is flush with the rear edges of the boxing walls 10. Between the flanges 105 is confined the vertical frame 49, for the purpose of guiding the seal. This frame also encloses the windowpane 35. The lower end of chute 42 registers with the seal-slot 40 in the casting, and is flared outwardly at 107 for the purpose of assisting easy insertion of the seal. The upper end of the chute 42 is turned back at 108 to help bend and guide the seal back through the slot 34 in the seal-locking bolt 29. In the back wall 48 of frame 49 there is a cutout 109, through which extends forwardly the two prong deflector 44, which co-operates with 108 in flexing or bending and guiding the seal through slot 34 in the seal-locking bolt 29, and in introducing the seal to the mesh of the gears. The window 35 is notched on the rear face at 45, into which notches the prongs 44 extend, thus insuring the seal being deflected backward to the gears.

The window 35 is provided with inturned points 74 upon its opposite sides, one point higher than the other. These points will make it difficult for a burglar to insert a new glass, if he should remove the original glass.

At Figure 13 is shown one form of seal, having its leading end 39 cut away at one corner 70, and having ribs 110 extending its entire length, one on each side of the indicia space. The shaped corner 70 permits entry of the seal into the slot-way, and at the same time insures the proper placing of the seal in reading position.

Figure 14 shows that if desired both leading corners may be cut away, as at 70, in some cases.

Figure 15 illustrates a yielding obstruction which will permit the entry of one form of seal, as for example Figure 14, but will prevent the introduction of a spurious seal having a square leading end. This device is in the form of a pawl 111, which is supported on a pivot 112^a, and is yielding so that it can be pressed to one side by the beveled edge 70 on the seal 33. It will be understood that if it were attempted to insert the square end of a seal, the same would abut the end of the pawl,

which could not thus be pushed to one side, and hence it would serve as an obstruction to prevent the seal from being introduced. An additional pawl 112 could be provided on the 5 opposite side of the seal slot-way, and each pawl could be double headed, as at 113, and both pawls could be made of one strip of metal, or of a single wire, as illustrated. The seal could be provided with an embossed 10 arrow-head 114, to indicate its leading end, and also to indicate the upper side of the seal.

At Figure 16 the windowpane 35 is shown as provided with parallel vertical grooves 115, in which may fit the seal-ribs 110 seen at Figure 13. It will be seen that if the original glass pane should be broken or removed, and a new one substituted without having said grooves 115, it would become impossible 20 to insert a seal, since the ribs 110 would be obstructed by the lower end of the glass pane. Moreover, this shaping of the glass pane would be effective in many instances in preventing the insertion of a spurious seal.

25 At Figures 17 and 18 is shown an interceptor 116 pivoted at 117 in the housing at the seal-chute, in position to intercept the leading end 118 of the seal seen at Figure 17; this interceptor being in the form of a tongue 30 whose tip is held against the inner face of the glass pane 35 by a spring 119. This interceptor 116 may be forced away from the pane by means of cams 120, which may be pressed in the leading end of the seal, and may have 35 beveled leading ends, to engage bevels 121 which are provided upon downwardly-extending arms 122, provided upon said interceptor 116. As the seal is thrust up, the leading bevels 120 engage the bevels 121, and 40 swing the arms 122 away from the glass, together with the intercepting tongue 116. These cams have dwell or rib portions 123 extending along the seal, to maintain the interceptor 116 away from the glass until the recessed 45 leading end 118 inserts itself between the glass and the tongue 116. Spurious seals will be 50 intercepted by the tongue 116, because there is nothing to lift it up from the glass. The bevels or teeth 121 do not touch the glass, but 55 leave a clearance, which would permit the passage of a spurious seal, which would then be caught upon the tongue 116 and arrested.

57 Figure 19 is a form of interceptor which may be used with the seal shown at Figure 13 and elsewhere. This interceptor is in the 58 form of a single pawl 124, pivoted at 125 and 60 pressed by a spring 126 to normal position. The pawl has a bevel 127 to enable the bevel 70 of the seal to press the pawl to one side, so that the seal may freely pass up into the chute 42. If it should be attempted to insert the seal the wrong way around, or if a spurious seal should be inserted, the same would 65 engage the abrupt end 128 of the pawl and be arrested.

At Figures 5 and 7 is shown one form of seal, which is mainly unstiffened, so that it may freely pass around the bend at 108, Figure 1. At its lower end the seal is provided with special short, longitudinal stiffening flanges 129, which convert this end of the seal 70 into a handle, for convenience in holding and inserting the seal, as it may be pressed up by the fingers without liability of crumpling, buckling or bending the seal. These finger-supports 129 may remain below the housing 75 and be of use in pressing up the seal, until it gets back of the bend and reaches the bite of the drawing rolls, as at Figure 1. These ribs 129 are preferably placed on opposite 80 sides of the seal, as shown, and the result is that the chute, at Figure 7, is completely filled by the seal, so that it is impossible to insert a second seal while the first one remains in the chute.

85 The same structure is seen at Figure 9, except that the stiffening ribs which form the finger-piece are on the same side of the seal as at 130, while a single longitudinal stiffening rib 131 may be formed upon the opposite side of the seal to extend the entire length thereof, or as far as desired.

90 Each seal may be also provided with miscellaneous thickening means, in the form of buttons or cups 132 pressed in the seal, to help fill up the seal-chute, so as to prevent another seal being inserted while one still remains in the slot-way. Each seal may be provided at its leading end with a hole 133, for convenience in carrying a number of seals 95 upon a wire or a hook.

98 Variations may be resorted to within the scope of the invention, and portions of the improvements may be used without others.

Having thus described my invention, I 103 claim:

1. The combination of a locking bolt, a tumbler mounted to interlock with said bolt, a destructible locking device introduced into 108 position to lock said tumbler against releasing said bolt, and means mounted to operate upon said device and withdraw it to tumbler-releasing position and mutilate the device and eject it.

2. The combination with a car door, of a 115 hasp upon the door, a lug over which the hasp is placed, a lock including a housing and having a bolt which is dropped over the hasp, a normally-released tumbler which is 120 shiftable into locking engagement with said bolt to prevent the latter from releasing the hasp, a locking seal which is thrust into the housing, said seal interlocking with the tumbler to prevent the latter from releasing said bolt, a pair of mutilating gears to draw 125 the seal within the housing, and means to guide the seal from the housing as it is delivered by said gears in the operation of releasing the tumbler and bolt.

3. Apparatus as set forth in claim 2, said 130

lock housing provided with an upper guide and a floor, and said bolt passing through said upper guide and through said floor to be guided thereby, said floor performing the functions of a rigid lug to co-operate with the first lug for retaining the hasp.

4. In a lock, the combination with a housing, a hasp, and a lug provided upon said housing, of an upright bolt bent into the form of an inverted U, one leg of which is longer than the other, the short leg co-operating with the lug to lock the hasp, and the long leg serving as a guide and projecting beyond the bottom of the housing to form a handle for lifting the bolt from the lug, upper guiding means engaging the short leg, means being provided to prevent the rotation of the bolt, said housing having a compartment for the short leg of said bolt, and a guiding arm retaining said short leg.

5. In a lock having a housing, the combination of a bolt in the form of an inverted U, one leg thereof being used to secure a hasp and the other leg thereof having a locking notch or shoulder, a tumbler in the form of a hook or tooth which is pivoted within the housing and provided with means to cause it to return to normal releasing position, said tumbler provided with a handle whereby it may be swung to bolt-locking position, said tumbler having means for guiding and interlocking with a destructible lock in the form of a seal, and means for advancing the seal and mutilating the same, said advancing and mutilating means being on the delivery side of the tumbler to draw the seal therethrough, the housing having a slot for the insertion of the seal, and said tumbler being between said slot and said mutilating and advancing means; said lock having a guideway from said slot to said tumbler, and the latter having a seal-slot which is out of register with said guideway or chute when the tumbler is in normal open position; said chute holding the seal against edgewise displacement and thereby interlocking with the tumbler to prevent release thereof without injuring the seal; and a window through which the seal is visible between said tumbler and said introductory slot.

6. In a device of the character described having a housing, the combination with a locking bolt, of means to lock the same, said locking means being perforated for engagement with a seal having raised letters, said housing having a seal-chute extending up from its bottom and including side walls for guiding the seal and enabling the seal to form an interlock between said locking means and said housing, a glass light in front of said chute and close thereto to leave only sufficient space for the passage of the seal with its raised letters, said locking means in the form of a tumbler, said chute being between said tumbler and said glass light, an inclined de-

flector within the housing and set at an angle to the path of the advance of the rising seal and formed to direct the seal rearwardly, said seal-chute having its upper portion inclined rearwardly so as to present the point of the seal at a more favorable angle to said deflector, recesses being cut in the glass light to accommodate the tips of the deflector, said deflector being forked so as to clear the raised portions along the middle of the seal, and a bracket having a rear support and forming a backing for the chute and also forming a frame for the window, said deflector secured to said bracket, and corrugated rolls in the rear of said deflector to bite the seal and draw it through the chute and mutilate it, a dog being provided to engage the mutilating device to prevent it from rotating backwardly, said mutilating device provided with a handle connected thereto by a clutch, so that the reversal of the handle cannot rotate the mutilating device.

7. The combination with a car door having a housing secured thereto, of a locking device mounted in the housing and including a vertical bolt of U form, said housing having a hasp-lug over which said bolt can drop, a tumbler within said housing in normal withdrawn position, a finger-piece for said tumbler to swing it into locking engagement with said U bolt, the latter having a slot into which the tumbler enters, said tumbler having a seal-slot normally covered, a seal-chute mounted within said housing, said tumbler by its locking movement bringing its seal-slot into register with said seal-chute, a seal-slot in the bottom of said housing below said chute, a seal thrust through said seal-slot and along said chute and passing through the slot in said tumbler and locking the same in engagement with said U bolt, seal-mutilating means engaging the leading end of said seal to draw it through the lock, and means preventing backward movement of said mutilating means, said housing having a slight-opening through which said seal is visible.

8. The combination of a locking bolt, a normally-ineffective tumbler movable to position to lock said bolt, said tumbler having a seal-slot, a housing having a seal-chute which is in line with said tumbler-slot when the slot is in locking position and means to draw the seal along said chute and through said tumbler-slot, means for preventing retrograde movement of said drawing means, the seal being destructible by said advancing means, and means to return said tumbler to a normal position upon the withdrawal of the seal therefrom by said advancing means.

9. Apparatus as recited in claim 4, said housing having a bottom in which is provided the seal-receiving slot, to permit the upward thrust of the seal, said bottom formed on its under side with a depression adjacent to the seal-slot, said depression shaped to corre-

130

spond to an asymmetrical form of the leading end of the seal, only the reduced end of the seal being insertible in the slot, said reduced end being insertible in only one position of the seal, the bottom of the housing having a grooving or shaping to lead or guide the seal to the slot when the seal has been properly presented to the groove; the grooved portion of the slot being bordered by a locating ledge to assist the fingers of the operator, said ledge being continued to the side of the housing and arched to form protection against the weather.

10. In a lock, the combination of a housing, a locking bolt therein, a tumbler mounted in said housing to interlock with said locking bolt, a seal-receiving, destroying and ejecting unit inserted in said housing and secured thereto, said unit including a frame which is bolted within the housing, said housing having a slot open in the rear and said unit having a boss extending through said slot, a seal-advancing and mutilating train including a shaft projecting through said boss and having an operating handle outside of the boss, said unit having a slanting wall-portion to close up an opening in the bottom of the housing, a set screw to serve as an adjustment for the general positioning of said unit in the housing, said unit having upper and lower meshing gears for advancing the seal, means to prevent said gears from being operated backwardly, a chute projecting into a seal-ejecting boss at the back of said unit, said unit having front and rear flanges for seating against the walls of the housing, a vertical frame being confined between said unit and the front of the housing and having flanges for the purpose of guiding the seal, and a window-pane enclosed in said frame.

11. Apparatus according to claim 10, the seal-chute extending upwardly and at its lower end registering with a seal-slot in the bottom of the housing, said chute flared outwardly at its lower end to assist in inserting the seal, said chute at its upper end being turned back to help bend and guide the seal back through the slot in the seal-locking tumbler or bolt, the back wall of said frame having a cutout through which extends forwardly the two pronged deflector which cooperates with the bend in the chute, to flex or bend the seal and guide it through the slot in the seal-locking tumbler, and introduce the seal to the bight of the advancing gears, said window having inturned points at its opposite sides, one point higher than the other.

12. The combination of a lock having a bolt, a seal, means to co-operate with said seal to lock the bolt, and means for preventing the introduction of the seal, said preventing means being releasable by means of a seal which is specially fitted thereto.

13. Apparatus according to claim 1, provided with a device to prevent introduction

of the seal, said preventing device being releasable by a specially constructed seal fitting thereto.

14. A pivoted seal interceptor in the form of a tongue and having forks projecting in advance of said tongue to engage bevels raised upon the leading end of the seal, the latter being cut away between said bevels, said raised portions having dwells to maintain the tongue in open position until the cut-away leading edge of the seal passes by said tongue.

15. Apparatus as set forth in claim 7, having a seal interceptor mounted in said chute and releasable only by a seal whose leading end is specially fitted thereto, and effective to block all other seals.

16. The combination with a car door, of a hasp upon the door, a lug over which the hasp is placed, a lock including a housing and having a bolt which is dropped over the hasp, a normally-released tumbler which is shiftable into locking engagement with said bolt to prevent the latter from releasing the hasp, a locking seal which is thrust into the housing, said seal interlocking with the tumbler to prevent the latter from releasing said bolt, a pair of mutilating gears to draw the seal within the housing, and means to guide the seal from the housing as it is delivered by said gears in the operation of releasing the tumbler and bolt, said lock housing provided with an upper guide and a floor, and said bolt passing through said upper guide and through said floor to be guided thereby, said floor performing the functions of a rigid lug to co-operate with the first lug for retaining the hasp.

17. The combination with a car door, of a hasp upon the door, a lug over which the hasp is placed, a lock including a housing and having a bolt which is dropped over the hasp, a normally-released tumbler which is shiftable into locking engagement with said bolt to prevent the latter from releasing the hasp, a locking seal which is thrust into the housing, said seal interlocking with the tumbler to prevent the latter from releasing said bolt, a pair of mutilating gears to draw the seal within the housing, means to guide the seal from the housing as it is delivered by said gears in the operation of releasing the tumbler and bolt, said lock housing provided with an upper guide and a floor, and said bolt passing through said upper guide and through

110 said floor to be guided thereby, said floor performing the functions of a rigid lug to co-operate with the first lug for retaining the hasp, said housing being open at its back, and bolts to secure the back of the housing against the car door, said housing having upper and lower extension-plates on its side wall and flanges to stiffen said extension-plates; said housing, flanges and plates being integral.

18. In a lock having a housing, the combi- 120

nation of a bolt in the form of an inverted **U**, one leg thereof being used to secure a hasp and the other leg thereof having a locking shoulder, a tumbler in the form of a tooth which is pivoted within the housing and provided with means to cause it to return to normal releasing position, said tumbler provided with a handle whereby it may be swung to bolt-locking position, said tumbler having means for guiding and interlocking with a destructible seal, and means for advancing the seal and mutilating the same.

19. In a lock having a housing, the combination of a bolt in the form of an inverted **U**, one leg thereof being used to secure a hasp and the other leg thereof having a locking shoulder, a tumbler in the form of a tooth which is pivoted within the housing and provided with means to cause it to return to normal releasing position, said tumbler provided with a handle whereby it may be swung to bolt-locking position, said tumbler having means for guiding and interlocking with a destructible seal, and means for advancing the seal and mutilating the same, said advancing and mutilating means being on the delivery side of the tumbler to draw the seal therethrough, the housing having a slot for the insertion of the seal, and said tumbler being between said slot and said mutilating and advancing means.

20. In a lock having a housing, the combination of a bolt in the form of an inverted **U**, one leg thereof being used to secure a hasp and the other leg thereof having a locking shoulder, a tumbler in the form of a tooth which is pivoted within the housing and provided with means to cause it to return to normal releasing position, said tumbler provided with a handle whereby it may be swung to bolt-locking position, said tumbler having means for guiding and interlocking with a destructible seal, and means for advancing the seal and mutilating the same, said advancing and mutilating means being on the delivery side of the tumbler to draw the seal therethrough, the housing having a slot for the insertion of the seal, and said tumbler being between said slot and said mutilating and advancing means; said lock having a guideway from said slot to said tumbler, and the latter having a seal-slot which is out of register with said guideway when the tumbler is in normal open position; said guideway holding the seal against edgewise displacement and thereby interlocking with the tumbler to prevent release thereof without injuring the seal.

21. In a lock having a housing, the combination with a locking bolt, of means to lock the same, said locking means being perforated for engagement with a seal having raised letters, said housing having a seal-chute extending up from its bottom and including side walls for guiding the seal and

causing said locking means to interlock with said housing, and confining means in front of said chute and close thereto to leave only sufficient space for the passage of the seal with its raised letters, said interlocking means in the form of a tumbler, said chute being between said tumbler and said confining means.

22. In a device of the character described having a housing, the combination with a locking bolt, of means including a tumbler to lock the same, said tumbler being perforated for engagement with a seal, said housing having a seal-chute including side walls for guiding the seal and thereby enabling the seal to form an interlock between said tumbler and said housing, and an inclined deflector within the housing and set at an angle to the path of the advance of the rising seal and formed to direct the seal rearwardly, said seal-chute having its upper portion inclined rearwardly so as to present the point of the seal at a more favorable angle to said deflector.

23. In a device of the character described having a housing, the combination with a locking bolt, of means including a tumbler to lock the same, said tumbler being perforated for engagement with a seal, having raised portions, said housing having a seal-chute including side walls for guiding the seal and thereby enabling the seal to form an interlock between said tumbler and said housing, and an inclined deflector within the housing and set at an angle to the path of the advance of the rising seal and formed to direct the seal rearwardly, said seal-chute having its upper portion inclined rearwardly so as to present the point of the seal at a more favorable angle to said deflector, said deflector being forked so as to clear the raised portions along the middle of the seal.

24. In a lock having a housing, the combination with a locking bolt, of means to lock the same, said locking means being perforated for engagement with a seal having raised letters, said housing having a seal-chute extending up from its bottom and including side walls for guiding the seal and causing said locking means to become interlocked with said housing, said interlocking means in the form of a tumbler, an inclined deflector within the housing and set at an angle to the path of the advance of the rising seal and formed to direct the seal rearwardly, said seal-chute having its upper portion inclined rearwardly so as to present the point of the seal at a more favorable angle to said deflector, said deflector being forked so as to clear the raised portions along the middle of the seal.

25. In a lock having a housing, the combination with a locking bolt, of means to lock the same, said locking means being perforated for engagement with a seal having raised letters, said housing having a seal-chute extending up from its bottom and including side walls for guiding the seal and

25. In a lock having a housing, the combination with a locking bolt, of means to lock the same, said locking means being perforated for engagement with a seal having raised letters, said housing having a seal-chute extending up from its bottom and including side walls for guiding the seal and causing said locking means to interlock with said housing, a glass light in front of said chute and close thereto to leave only sufficient space for the passage of the seal with its raised letters, said interlocking means in the form of a tumbler, said chute being between said tumbler and said glass light, an inclined deflector within the housing and set at an angle to the path of the advance of the rising seal and formed to direct the seal rearwardly, said seal-chute having its upper portion inclined rearwardly so as to present the point of the seal at a more favorable angle to said deflector, said glass light having recesses to accommodate the tips of the deflector, said deflector being forked so as to clear the raised portions along the middle of the seal, and a bracket having a rear support and forming a backing for the chute and also forming a frame for the window, said deflector secured to said bracket.

26. The combination with a car door having a housing secured thereto, of a locking device mounted in the housing and including a vertical bolt of U form, said housing having a hasp-lug through which said bolt can drop, a tumbler within said housing in normal withdrawn position, a finger-piece for said tumbler to swing it into locking engagement with said U bolt, the latter having a slot into which the tumbler enters, said tumbler having a seal-slot normally covered, a seal-chute mounted within said housing, said tumbler by its locking movement bringing its seal-slot into register with said seal-chute, a seal-slot in the bottom of said housing below said chute adapted to receive a seal thrust through said seal-slot and along said chute and through the slot in said tumbler to lock the same in engagement with said U bolt, seal-mutilating means adapted to engage the leading end of said seal to draw the seal through the lock, and means preventing backward movement of said mutilating means.

27. In a device of the character described, the combination of a locking bolt, a normally-ineffective tumbler movable to position to lock said bolt, said tumbler having a seal-slot, a housing having a seal-chute which is in line with said tumbler-slot when the slot is in locking position and means engageable with the seal to mutilate the seal and draw it along said chute and through said tumbler-slot and out of the device.

28. In a device of the character described having a housing, the combination with a locking bolt, of means including a tumbler

to lock the same, said tumbler being perforated for engagement with a seal, said housing having a seal-chute including side walls for guiding the seal and enabling it to cause an interlock between said tumbler and said housing, and corrugated rolls to bite the seal and draw it through the chute and mutilate it, a dog being provided to engage the mutilating device to prevent it from rotating backwardly, said mutilating device provided with a handle connected thereto by a clutch, so that the reversal of the handle cannot rotate the mutilating device.

29. In a lock, the combination of a housing, a locking bolt therein, a tumbler having a seal-slot and mounted in said housing for becoming interlocked with said locking bolt, a unit inserted in said housing and secured thereto, said unit including a frame which is bolted within the housing, said housing having a slot open in the rear and said unit having a boss extending through said slot, said unit having a shaft projecting through said boss and provided with an operating handle outside of the boss, a set-screw to serve as an adjustment for the general positioning of said unit in the housing, said unit including upper and lower meshing gears driven by said shaft for advancing and mutilating the seal, and means to prevent said gears from being operated backwardly.

30. In a lock, the combination of a housing, a locking bolt therein, a tumbler having a seal-slot and mounted in said housing for becoming interlocked with said locking bolt, a unit inserted in said housing and secured thereto, said housing having a slot open in the rear and said unit having a boss extending through said slot, a shaft projecting through said boss and having an operating handle outside of the boss, said unit having meshing gears for advancing the seal, means to prevent said gears from being operated backwardly, and a chute projecting into a seal-ejecting boss at the back of said unit.

31. In a lock, the combination of a housing, a locking bolt therein, a tumbler having a seal-slot and mounted in said housing to become interlocked with said locking bolt, a unit inserted in said housing and including a frame, said housing having a slot and said unit having a boss extending through said slot, a shaft projecting through said boss and having an operating handle, said unit having meshing gears for mutilating and advancing a seal, means to prevent said gears from being operated backwardly, said unit having opposite flanges for seating against the walls of the housing, a vertical frame confined between said unit and the front of the housing and having flanges for the purpose of guiding the seal, and a window-pane enclosed in said frame.

32. In a lock, the combination of a housing, a locking bolt therein, a seal-locking

tumbler having a seal-slot and mounted in said housing to become interlocked with said locking bolt, a unit inserted in said housing, the latter having an open slot and said unit having a boss extending through said slot, a seal-advancing and mutilating train including a shaft projecting through said boss and having an operating handle outside of the boss, means to prevent said train from being operated backwardly, a seal-ejecting boss, and a seal-chute projecting into the seal-ejecting boss, the seal-chute extending upwardly and at its lower end registering with a seal-slot in the bottom of the housing, said chute at its upper end being turned back to bend and guide the seal through the slot in the seal-locking tumbler.

33. In a lock, the combination of a housing, a locking bolt therein, a tumbler having a seal-slot and mounted in said housing for becoming interlocked with said locking bolt, a unit inserted in said housing and including a frame, said housing having a slot and said unit having a boss extending through said slot, a seal-advancing and mutilating train including a shaft projecting through said boss and having an operating handle outside of the boss, said unit having meshing gears for advancing and mutilating the seal, means to prevent said gears from being operated backwardly, and a chute extending inwardly and at its outer end registering with a seal-slot in the bottom of the housing, said chute at its inner end being turned to guide the seal through the slot in the seal-locking tumbler, a deflector, the wall of said frame having a cutout through which extends forwardly the deflector, the deflector being co-operative with the bend in the chute, to flex the seal and guide it through the slot in the seal-locking tumbler, and introduce the seal to the bight of the advancing gears.

34. In a lock, the combination of a housing, a locking bolt therein, a tumbler having a seal-slot and mounted in said housing for becoming interlocked with said locking bolt, a unit inserted in said housing and including a frame, a seal-advancing and mutilating gear-train including a shaft projecting through a boss and having an operating handle outside of the boss, a vertical frame being confined between said unit and the front of the housing and having flanges for the purpose of guiding the seal, a window-pane enclosed in said frame, and a seal-chute extending upwardly and at its lower end registering with a seal-slot in the bottom of the housing.

CLARENCE R. MARTINEAU.
